(57) **CLAIM**

The ornamental design for a vehicle brake, as shown and described.

DESCRIPTION

FIG. 1 is a perspective view of a vehicle brake showing my new design;

FIG. 2 is a front side view of the vehicle brake shown in FIG. 1;

FIG. 3 is a rear side view of the vehicle brake shown in FIG. 1;

FIG. 4 is a left side view of the vehicle brake shown in FIG. 1;

FIG. 5 is a top view of the vehicle brake shown in FIG. 1; and

FIG. 6 is a bottom view of the vehicle brake shown in FIG. 1.

The dashed broken lines in the drawing depict portions of vehicle brake that form no part of the claimed design.
